Primary Examiner — Paul D Bohannon(74) *Attorney, Agent, or Firm* — Fulwider Patton LLP(57) **CLAIM**

The ornamental design for a chair, as shown and described.

DESCRIPTION

FIG. 1 is an elevated front perspective view of my chair showing my new design.

FIG. 2 is a top view thereof;

FIG. 3 is front view thereof;

FIG. 4 is a bottom view thereof;

FIG. 5 is a left side view thereof;

FIG. 6 is a right side view thereof;

FIG. 7 is a rear view thereof.

FIG. 8 is a front elevated perspective view thereof, shown in a first environmental context;

FIG. 9 is a rear bottom perspective view thereof, shown in a second environmental context; and,

FIG. 10 is a rear bottom perspective view thereof, shown in a third environmental context.

The broken lines in FIGS. 8, 9 and 10 show environmental structure and form no part of my invention.

1 Claim, 5 Drawing Sheets**FIG. 1**

FIG. 2**FIG. 3****FIG. 4**

FIG. 5**FIG. 6****FIG. 7**

FIG. 8

FIG. 9**FIG. 10**
